UNITED STATES PATENT OFFICE

2,643,501

WRAPPING MACHINE

Alexander Russell, Leeds, England, assignor to
 The Forgrave Machinery Company Limited,
 Leeds, England, a company of Great Britain

Application February 4, 1952, Serial No. 269,884
 In Great Britain February 15, 1951

6 Claims. (Cl. 53—135)

1

This invention relates to machines for wrapping shaped blocks of plastic materials, such for example as butter, margarine or the like, of the kind described for example in U. S. Patent No. 2,379,655, comprising an intermittently rotating wrapping wheel having a number of pockets arranged to be brought in succession to a receiving station, and a lifting member for lifting into each pocket, while it dwells at the receiving station, a block of plastic material together with a wrapper, which is fed into position between the pocket and the block and folded in U formation about the block as it is lifted into the pocket.

It has been the customary practice in such machines to provide each pocket of the wrapping wheel with a fixed base plate and a pair of pivoted side jaws. The use of a fixed base plate, however, has the disadvantage that wrinkles may form in the portion of the wrapper adjoining the top of the block as the latter is lifted into the pocket. Furthermore, correct register of the wrapper in relation to the block is dependent solely upon adhesion between the wrapper and the block during the lifting of the block into the pocket, and this adhesion is sometimes insufficient.

This invention provides a wrapping machine of the above kind, in which each pocket of the wrapping wheel comprises a movable base plate and pivoted side jaws, and which comprises mechanism operating in timed relationship with the lifting member for moving downwardly the base plate of the pocket of the wrapping wheel at the receiving station and simultaneously opening the side jaws preparatory to arrival of the block in the pocket, and thereafter raising the base plate and gradually closing the side jaws on the block as the latter is lifted into the pocket.

In this way I ensure that the wrapper will lie smoothly on the upper surface of the block and that the wrapper will be tightly folded in U-formation against the sides of the block.

Preferably, the base plate of each pocket is resiliently mounted on a bar which, on arrival of the pocket at the receiving station, is moved up and down in relation to the wrapping wheel by a cam mechanism and is linked to the side jaws so as to impart opening and closing movements thereto. This allows the initial impact of the top of the block against the base plate to be taken up together with the amount of acceleration required by the bar to enable it to reach, on its up stroke, the same speed as the

2

speed of upward movement of the lifting member. The flexible mounting of the base plate also allows for vibration in the height of the block of plastic material.

5 One specific embodiment of wrapping machine according to the invention will now be described in detail, by way of example, with reference to the accompanying drawings, in which:

10 Fig. 1 is a front elevation of the wrapping wheel and associated lifting plunger,

Fig. 2 is a sectional elevation, on a larger scale, showing the pocket of the wrapping wheel at the receiving stage and in position to receive

15 the block of material to be wrapped,

Fig. 3 is a view similar to Fig. 2, but showing the jaws of the pocket closed, this figure being a section on the line III—III in Fig. 4,

Fig. 4 is a side elevation of part of the wrapping wheel, looking from the right hand side of Fig. 3,

Fig. 5 is a section on the line V—V in Fig. 3, and

Fig. 6 is an enlarged detail perspective view, 25 showing the spring mounting of the base plate.

Like reference numerals denote like parts throughout the figures.

The machine illustrated is of the general character described in U. S. Patent No. 2,379,655. 30 The wrapping wheel 10 is mounted to rotate on a fixed horizontal shaft 11 and is fixed to a gear wheel 12 (Fig. 4), also rotatable on the shaft 11, meshing with another gear (not shown) driven by a Geneva mechanism (also not shown), which imparts intermittent movement to the wrapping wheel 10. The wrapping wheel 10 is attached to the gear wheel 12 by a sleeve 13 having at its ends bearing bushings which fit the shaft, and the resulting unit is disposed on the shaft between a collar 14 and a circular member 15, both of which are fixed to the shaft 11.

The wrapping wheel has four pockets 16 which are brought successively, by rotation of the wrapping wheel, to a bottom receiving station A (Fig. 1), a folding station B, a top pressing station C and a discharge station D, these stations being spaced 90° apart. 40

As each pocket 16 dwells at the receiving station A, a block 17 of plastic material is lifted into the pocket by a lifting member 18 (Fig. 1), which is reciprocated by a linkage 19 deriving movement from a cam 20 as described in U. S. Patent No. 2,379,655. A pusher 21 feeds the blocks in succession onto the top of the lifting member 18 while it is dwelling in the bottom

position shown in Fig. 1. Wrappers 22 are fed in succession into the path of the lifting member 18, as described in U. S. Patent No. 2,374,838, so that a wrapper is folded in U-formation about each block as the latter is lifted into the pocket, by the base plate 23 and side jaws 24 of the pocket which will be described later. Prior to arrival of the pocket at the folding station, the depending ends of the wrapper are folded against the base of the block. At the folding station B, side tucks are formed in the projecting ends of the wrapper and these ends are folded against the surface of the block remote from the centre of the wrapping wheel. During the travel of the block to the top pressing station C it passes between fixed end plates having slots which fold down against the ends of the block the projecting triangular wings of the wrapper which are left projecting at the folding station. At the top pressing station, a top presser descends onto the top of the block to ensure correct shaping thereof and finally, at the discharge station D, the block is discharged from the pocket in a direction parallel to the base plate thereof. The operations taking place at the stations B, C and D will not be described in more detail as they form no part of the present invention.

The base plate 23 of each pocket is carried on a bar 25 mounted in guides 26 on the wrapping wheel so that it may slide radially in relation to the wrapping wheel. The base plate 23 is resiliently supported on the bar 25 by compression springs 27, which tend to hold the base plate projected from the bar. As will be clear from Fig. 6, a bracket 28 is attached to the base plate 23 and fixed by bolts 29 to a plate 30 formed with a cavity embracing a waisted portion 25a of the bar 25. The lower ends of the springs 27, which lie one on each side of the bar 25, are accommodated in tubular bosses 31 in the bracket 28 and the plate 30 respectively, while their upper ends are accommodated in tubular bosses 32 on plates 33 fixed by a bolt 34 to the bar 25. The springs 27 normally hold the base plate projected beyond the lower end of the bar 25 as shown in Fig. 2. The springs 27, however, can yield when necessary to permit of limited upward movement of the base plate in relation to the bar.

A stud 35, passing through the upper ends of the plates 33 and the bar 25 and extending parallel to the shaft 11 of the wrapping wheel, carries a roller 36 (Fig. 5) which runs in an annular track 37 in the circular member 15. Each side jaw 24 of each pocket is mounted on a pivot pin 38 extending parallel to the shaft 11 of the wrapping wheel and is integral with an upwardly extending arm 39 connected by a link 40 to an arm 41 integral with one of the plates 33. Consequently, as the bar 25 and base plate 23 move outwardly on the wrapping wheel, from the position of Fig. 3 to that of Fig. 2, the side jaws 24 will be opened, and vice versa.

A section 15a of the circular member adjoining the receiving station A, which section contains part 37a of the annular track, is movable in relation to the rest of the circular member and is attached by a bolt 43 (Fig. 5) to a lever 42, pivoted at 44 (Fig. 1) to the machine frame and actuated by a cam 45. Normally, the section 15a occupies the position shown in Fig. 3 in which its portion 37a of the track 37 is aligned with the remainder of the track. Each time, however, a pocket approaches the receiving station A, and after the roller 36 on the stud 35 of that pocket has entered the portion 37a of the

track in the movable section 15a of the circular member 15, the cam 45 moves the movable section 15a into the position shown in Fig. 2 and thereby slides the bar 25 and base plate 23 downwards and opens the side jaws 24 of the pocket. The movement is timed to open the side jaws 24 to the maximum and to depress the base plate 23 to its lowest position, in which it is disposed immediately above the wrapper 22, as shown in Fig. 1, as the pocket begins to dwell at the receiving station.

The block 17 of margarine pushed upwards by the lifting member 18 first contacts the wrapper 22 and then contacts the base plate 23 of the pocket immediately afterwards. This flattens the wrapper over the whole of the top surface of the block and prepares the way for clean tight folding of the wrapper round the block. As the block rises into the pocket, the cam 45 gradually returns the movable section 15a to its normal position. The resulting gradual closing of the side jaws 24 as the block rises into the pocket ensures tight folding of the wrapper onto the sides of the block.

As already noted, the flexible mounting of the base plate 23 on the bar 25 allows for the initial impact of the top of the margarine block plus the amount of acceleration required by the operating movement to reach the same speed as the block lifter movement.

After return of the pockets to the position shown in Fig. 3, the wrapping wheel commences its movement to carry the partially wrapped block to the folding station B. During the remainder of the rotation of the wrapping wheel, and until the pocket in question again reaches the receiving station A, the annular track 37 coacts with the stud 36 to maintain the bar 25 in the retracted position and the side jaws 24 closed on the block of plastic material. In this position, as shown in Fig. 3, the inner face of the base plate is closely adjacent to shoulders 50 on the side jaws. Consequently, when the block is pressed at the top pressing station C, the resilient connection between the base plate and the bar can only yield to a very slight extent and the full pressure of the top presser is taken by these shoulders 50.

The circular member 15 has been described as having a simple annular track 37 and but one movable section 15a adjacent the receiving station A, and this will be sufficient because the soft mass of the margarine or butter permits discharge, at the discharge station D, of the blocks from the pockets in a direction parallel with the base plate 23 without it being necessary to open the side jaws 24 at the discharge station. If desired, however, the track 37 may have an offset portion, in the vicinity of the discharge station D, which will operate to displace the roller 36 and bar 25 in the direction to give a small opening to the side jaws 24 as the pocket arrives at the discharge station D.

What I claim as my invention and desire to secure by Letters Patent is:

1. A machine for wrapping shaped blocks of plastic material, comprising a wrapping wheel disposed with its axis horizontal and having a number of pockets, each comprising a movable base plate and pivoted side jaws, means for imparting intermittent rotation to said wrapping wheel to bring said pockets in succession to a receiving station said pockets extending downwardly when at said receiving station, an intermittently operating lifting member for lifting

into each of said pockets as it dwells at the receiving station a block of plastic material with a wrapper folded in U-formation about it, and mechanism, operating in timed relationship with the lifting member, for moving downwardly the base plate of the pocket at the receiving station and simultaneously opening the side jaws of said pocket preparatory to arrival of the block in the pocket and thereafter raising said base plate and gradually closing said side jaws on the block as the latter is lifted into the pocket.

2. A machine for wrapping shaped blocks of plastic material, comprising a wrapping wheel disposed with its axis horizontal and having a number of pockets, each comprising a bar movable radially in relation to the wheel, a base plate resiliently mounted on the end of said bar, a pair of pivoted side jaws and linkages for imparting pivotal movement to the side jaws from said bar, means for imparting intermittent rotation to said wrapping wheel to bring said pockets in succession to a receiving station said pockets extending downwardly when at said receiving station, an intermittently operating lifting member for lifting into each of said pockets as it dwells at the receiving station a block of plastic material with a wrapper folded in U formation about it, and mechanism, operating in timed relationship with the lifting member, for operating the bar of the pocket at the receiving station to lower the base plate and open the side jaws of said pocket preparatory to arrival of the block in the pocket and thereafter to raise said base plate and gradually close said side jaws on the block as the latter is lifted into the pocket.

3. A machine for wrapping shaped blocks of plastic material, comprising a wrapping wheel disposed with its axis horizontal and having a number of pockets, each comprising a bar movable radially in relation to the wheel, a base plate on the end of said bar, a pair of pivoted side jaws and linkages for imparting pivotal movement to the side jaws from said bar, means for imparting intermittent rotation to said wrapping wheel to bring said pockets in succession to a receiving station said pockets extending downwardly when at said receiving station, an intermittently operating lifting member for lifting into each of said pockets as it dwells at the receiving station a block of plastic material with a wrapper folded in U formation about it, a fixed member adjoining and coaxial with the wrapping wheel, said fixed member having therein an annular track and comprising a movable portion adjoining the receiving station, studs on the bars of all the

5 pockets which engage in said annular track, a cam mechanism coacting with said movable portion of the track so as to move the same, while a pocket is dwelling at the receiving station, and thereby to move the bar of said pocket, through the agency of the stud thereon, to lower the base plate of said pocket and simultaneously to open the side jaws thereof and thereafter, as the block rises into said pocket, to raise said base plate and close said side jaws.

10 4. A wrapping machine as claimed in claim 3 comprising springs between each base plate and the associated bar for permitting limited upward movement of the base plate in relation to the bar 15 while the block is being lifted into the pocket.

15 5. A wrapping machine as claimed in claim 4, in which the side jaws of each pocket have, on the inner faces of the jaws and near the pivots thereof shoulders which, when the side jaws are closed, coact with the base plate to prevent any substantial inward movement thereof in relation to the bar.

20 6. A machine for wrapping shaped blocks of plastic material, comprising a wrapping wheel disposed with its axis horizontal and having a number of pockets, each comprising a movable base plate and pivoted side jaws, means for imparting intermittent rotation to said wrapping wheel to bring said pockets in succession to a receiving station, said pockets extending downwardly when at said receiving station, an intermittently operating lifting member for lifting into each of said pockets as it dwells at the receiving station a block of plastic material with a wrapper

25 folded in U-formation about it, mechanism, operating in timed relationship with the lifting member, for first moving downwardly the base plate of the pocket at the receiving station into position close to the wrapper and thereafter raising said base plate as the lifting member lifts the wrapper and block into the pocket, and linkages connecting said base plate to said side jaws and arranged to open said side jaws as said base plate moves downwards and gradually to close 30 said side jaws as said base plate moves upwards.
